UNITED STATES PATENT OFFICE.

EDWARD CRAIG, OF ST. JOSEPH, MICHIGAN.

BOX AND PROCESS OF MANUFACTURE THEREOF.

1,208,297.

Specification of Letters Patent. Patented Dec. 12, 1916.

Application filed April 24, 1916. Serial No. 93,066.

To all whom it may concern:

Be it known that I, EDWARD CRAIG, a citizen of the United States of America, and resident of St. Joseph, Berrien county, Michigan, have invented a certain new and useful Improvement in Boxes and Processes of Manufacture Thereof, of which the following is a specification.

My invention relates to boxes of that kind in which the four sides are secured to rectangular end-walls, and in which means are provided for reinforcing the ends of the box along the edges thereof, as by providing the same with cleats and binding-wires, such as the ordinary or well-known wire-bound boxes.

Generally stated, the object of my invention is to provide an improved construction and arrangement, and an improved or novel process of manufacture, whereby some of the cleats are first fastened to one or more sections of the box-blank, while other cleats are fastened to the end-walls, and whereby the box-blank thus partially reinforced by cleats can then be folded around the end-walls which are also partially reinforced by cleats, and whereby the cleats of the box-blank can then be fastened to the end-walls, so that the cleats which are first fastened to the end-walls can afterward be fastened to the sections of the blank which were not provided with cleats, thus making it possible to have the end-walls reinforced by cleats before they are fastened to the box-blank, which is especially advantageous when each end-wall is composed of two or more separate strips of sheet-material, and thereby making it possible to have the cleats of the box-blank of such length that the opposite ends of each cleat are even with the edges of the sheet-material to which they are attached, which is also advantageous in various ways, as will hereinafter more fully appear.

It is also an object to provide an improved construction and arrangement and process of manufacture which will obviate the necessity of using certain features of construction and methods and machines heretofore considered necessary or desirable in the manufacture of boxes of this class.

To the foregoing and other useful ends, my invention consists in matters hereinafter set forth and claimed.

In the accompanying drawings: Figure 1 is a perspective of a box-blank embodying the principles of my invention. Fig. 2 is a

perspective of a box-end embodying the principles of my invention. Fig. 3 is an end view of a box constructed in accordance with my invention. Fig. 4 is a vertical section on line 4—4 in Fig. 3. Fig. 5 is a perspective of said box.

As thus illustrated, my invention comprises a box-blank A having four box-side-sections 1, 2, 3 and 4 which are flexibly connected together by the parallel binding-wires 5, 6 and 7 secured to the outer surface thereof by staples. On its inner surface said box-blank is reinforced at the side edges thereof by cleats 8 and 9 secured, respectively, to the sections 1 and 3, so that each of these sections is provided with a cleat at each side-edge of the blank. These cleats are each provided at opposite ends with a tongue 10 and a groove 11, and the ends of these cleats are exactly even with the edges of the sections 1 and 3, it being understood that all of these box-side-sections are made of veneer or other sheet-material. The staples which hold the wires 5 and 7 in place serve also to secure the cleats 8 and 9 to the under or inner side of the blank.

Each box-end-wall B is provided at two edges thereof with cleats 12 and 13, and at the center with a shorter cleat 14, the latter having blunt ends, but the cleats 12 and 13 being provided with a tongue-and-groove formation previously described. With this construction, the end-wall may be composed of two or more separate strips b of veneer or other sheet-material, inasmuch as the cleats 12, 13 and 14, or at least the cleat 14, will serve as battens or binding-members to hold the several strips tightly together before these end-walls are incorporated in the box.

The method of combining the box-blank with the end-walls is as follows: The cleats 8 are adjusted in position to interlock with the cleats 12 and 13, and the section 2 is then folded flatwise against the cleats 13, after which the section 3 is folded to bring the cleats 9 into interlocking engagement with the lower ends of the cleats 12 and 13, as shown in Fig. 3, thus forming a rectangular box with an open cover. The cleats 8 and 9 are then fastened by staples or nails, or in any suitable manner, to the sheet-material of the end-walls, and the cleats 12 and 13 are fastened by staples or nails to the sheet-material of the sections 2 and 4 of the blank,

but the section 4 is, of course, not thus fastened in place until after the box is filled, as this section forms the box-cover. The opposite ends of the wires 5, 6 and 7 are then 5 twisted together, in the manner shown, to form three practically continuous binding-members around the box.

With the foregoing construction, the edges of sections 2 and 4 overlap the edges 10 of sections 1 and 3, as shown in Fig. 3, thus forming tight corners for the box, notwithstanding that the ends of the cleats 8 and 9 are even or flush with the edges of the sections 1 and 3. As some of the cleats are 15 fastened to the end-walls before the latter are incorporated in the box, it follows that the mere folding of the blank around the end-walls serves to hold the latter in place, as the cleats on the end-walls interlock with 20 those on the blank, thus making it possible to easily and conveniently handle and manipulate the box before and during the operation of stapling or nailing the end-walls to the cleats of the blank, as well as while 25 fastening the blank to the cleats of the end-walls. The staples for the wires 5, 6 and 7 may be clenched on the under or inner surface of the box-side-sections 2 and 4 in any suitable manner. Thus some cleats are 30 fastened to one or more but not all of the sections of the box-blank, while one or more of the box-blank-sections are not provided with cleats. This results in a blank which is easily folded, and which can only fold in 35 the correct manner. As the center cleats 14 are usually necessary in boxes of this kind, it is very easy and requires practically no more time to fasten the cleats 12 and 13 to the box-end during the same operation, so 40 that the three cleats are secured in place at the same time.

With the foregoing construction, it is also obvious that the foldable-blank and the end-walls can be combined without any stapling 45 or nailing—that is to say, the blank can be folded around the end-walls, and the box can then be filled, without having stapled or nailed the end-walls in place, and the ends of the binding-wires can then be twisted together. Thus, the box can be shipped in a knocked-down condition, can be assembled 50 and filled without any stapling or nailing, the twisting of the ends of the binding-wires together constituting the only means for holding the box in shape. In this way after the box is opened and the contents 55 thereof are removed, the blank and the end-walls can then be knocked down and returned in a flat condition. Thus a flexible 60 blank is made by securing the parallel binding members to the outside thereof, to flexibly connect together the several box side sections, and parallel rows of cleats are secured to the inside of the blank, but with 65 gaps left in said rows, whereby the blank

is only partially cleat-reinforced before it is secured to the other cleats which are thereafter used to fill said gaps in the rows. Preferably, these gaps are opposite each other, as shown, and preferably the cleats 70 12 and 13 are secured to the end walls B before these cleats are used for filling in the gaps left in the rows of cleats on the blank; but for the broader purposes of my invention I do not, of course, limit myself to the exact construction, nor to the exact method or process shown and described.

What I claim as my invention is:—

1. A foldable box-blank comprising a plurality of box-side-sections composed of 80 sheet-material and flexibly connected together by binding-members extending parallel on the outer surface of the blank and beyond the end thereof and having only one but not all of said box-side-sections 85 provided with cleats on the inner surface of the box-blank.

2. A foldable box-blank comprising a plurality of box-side-sections composed of 90 sheet-material and flexibly connected together by binding-members extending parallel on the outer surface thereof and having some but not all of said box-side-sections provided with cleats on the inner surface of the box-blank, said cleat-reinforced-box- 95 side-sections being two in number, and there being the same number of box-side-sections which are not thus reinforced, and said cleats having their opposite ends even with the 100 edges of the sheet-material.

3. A foldable box-blank comprising a plurality of box-side-sections composed of 105 sheet-material and flexibly connected together by binding-members extending parallel on the outer surface thereof and having some but not all of said box-side-sections provided with cleats on the inner surface of the box-blank, said cleat-reinforced-box-side-sections being two in number, and there being the same number of box-side-sections 110 which are not thus reinforced, and said cleats having their opposite ends even with the edges of the sheet-material, said box-side-sections being spaced apart to allow the edges thereof to overlap at the corners 115 of the box in the manner shown and described.

4. Means to form a cleat-reinforced-box, comprising a foldable blank having only two of the box-side-sections thereof reinforced 120 by cleats, and box-ends having cleats for attachment to the box-side-sections which are not thus reinforced.

5. Means to form a cleat-reinforced-box, comprising a foldable blank having only two of the box-side-sections thereof reinforced 125 by cleats, and box-ends having cleats for attachment to the box-side-sections which are not thus reinforced, said box-side-sections comprising sheet-material the edges of 130

- which are even with the opposite ends of said cleats thereof, and said box-ends comprising sheet-material the edges of which are flush with the ends and outer sides of the cleats secured thereto.
6. Means to form a cleat-reinforced-box, comprising a foldable blank having only two of the box-side-sections thereof reinforced by cleats, and box-ends having cleats 10 for attachment to the box-side-sections which are not thus reinforced, said box-side-sections being separate and provided with binding-wires by which they are flexibly connected together.
15. 7. The process of making a box having cleats at the ends thereof, which comprises the making of a flexible blank by connecting together the sections thereof and securing some of said cleats thereto, leaving one or 20 more sections of the blank without cleats, making box-ends by securing the remaining cleats thereto so that each box-end is provided with cleats only at certain edges thereof, folding the blank around said box-ends, 25 securing the cleats of the blank to said box-ends, and securing the cleats of the box-ends to said blank.
8. The process of making a box, which comprises the making of a flexible blank 30 by connecting together the sections thereof, and securing some of said cleats thereto, leaving one or more sections of the blank without cleats, making box-ends by securing the remaining cleats thereto so that each box-35 end is provided with cleats only at certain edges thereof, folding the blank around said box-ends, securing the cleats of the blank to said box-ends, and securing the cleats of the box-ends to said blank, the making of the 40 blank including the attachment of binding-wires to flexibly connect together the previously unconnected sections thereof.
9. The process of making a box, which comprises the making of a flexible blank by 45 connecting together the sections thereof and securing some of said cleats thereto, leaving one or more sections of the blank without cleats, making box-ends by securing the remaining cleats thereto so that each box-end 50 is provided with cleats only at certain edges thereof, folding the blank around said box-ends, securing the cleats of the blank to said box-ends, and securing the cleats of the box-ends to said blank, the making of the blank 55 involving the separation of the edges of the sections and the positioning of the opposite ends of the cleats thereof even with some of said edges.
10. A box-end having cleats disposed on 60 the outer surface thereof and secured thereto at opposite edges only, flush with said edges, and having spaces between the ends of said cleats at the other edges thereof.
11. A box-end having cleats secured there-65 to at opposite edges only, having spaces be-
- tween the ends of said cleats at the other edges thereof, and four box-side-sections two of which have cleats to occupy said spaces and the other two of which are adapted for attachment to the cleats on the 70 box-end.
12. A box-end having cleats secured thereto at opposite edges only, having spaces between the ends of said cleats at the other edges thereof, and four box-side-sections 75 two of which have cleats to occupy said spaces and the other two of which are adapted for attachment to the cleats on the box-end, said cleats having ends which are even with the edges of the box-end, and a 80 shorter cleat in the middle of the box-end.
13. The process of making a box having cleats at the ends thereof, which comprises the making of a flexible blank by connecting together the sections thereof and securing 85 some of said cleats thereto, leaving one or more sections of the blank without cleats, making box-ends by securing the remaining cleats thereto so that each box-end is provided with cleats only at certain edges 90 thereof, folding the blank around said box-ends, causing the cleats of the blank to alternate with and engage the cleats of the box-ends.
14. Means to form a cleat-reinforced-box 95 comprising a foldable blank having the box-side-sections thereof reinforced by parallel longitudinal rows of cleats, with gaps in said rows, and box-ends having cleats to fill the gaps in said rows.
15. Means to form a cleat-reinforced-box comprising a foldable blank having the box-side-sections thereof reinforced by parallel longitudinal rows of cleats, with gaps in said rows, and box-ends having cleats to 105 fill the gaps in said rows, said cleats being formed with tongue-and-groove ends to interlock and thereby hold said box-ends in place.
16. The process of making a box having 110 cleats at the ends thereof, which comprises the making of a flexible blank by connecting together the sections thereof and securing some of said cleats thereto, making box-ends by securing the remaining cleats thereto so 115 that each box-end is provided with cleats only at certain edges thereof, folding the blank around said box-ends, securing the cleats of the blank to said box-ends, and securing the cleats of the box-ends to said 120 blank.
17. The process of making a box having cleats at the ends thereof, which comprises the making of a flexible blank by connecting together the sections thereof and securing some of said cleats thereto, making box-ends by securing the remaining cleats thereto so 125 that each box-end is provided with cleats only at certain edges thereof, folding the blank around said box-ends, causing the 130

cleats of the blank to alternate with and engage the cleats of the box-ends.

18. The process of making a wire-bound box having cleats at the ends thereof, which comprises the making of a flexible blank by securing parallel continuous binding wires to the outside of the box-side-sections, to flexibly connect the sections together and provide the encircling wire binding for the box, and securing some of said cleats to the inside of the blank, thereby forming parallel rows of cleats with gaps therein, and thereafter securing the remaining cleats in

said gaps and closing the ends of the box with end walls.

15

19. Means to form a cleat-reinforced-box comprising a foldable blank having the box-side-sections thereof reinforced by parallel longitudinal rows of cleats, with gaps in said rows, and end-walls to close the ends 20 of the box and other cleats to fill the gaps in said rows.

Signed by me at Chicago, Illinois, this 22nd day of April, 1916.

EDWARD CRAIG.

It is hereby certified that in Letters Patent No. 1,208,297, granted December 12, 1916, upon the application of Edward Craig, of St. Joseph, Michigan, for an improvement in "Boxes and Processes of Manufacture Thereof," an error appears in the printed specification requiring correction as follows: Page 2, line 84, claim 1, after the word "one" insert the words *or more*; and that the said Letters Patent should be read with this correction therein that the same may conform to the record of the case in the Patent Office.

Signed and sealed this 6th day of February, A. D., 1917.

[SEAL.]

R. F. WHITEHEAD,

Acting Commissioner of Patents.
